UNITED STATES PATENT OFFICE.

ORAZIO BONACORSO, OF PHILADELPHIA, PENNSYLVANIA, ASSIGNOR OF ONE-HALF
TO GEORGE LO BUE, OF PHILADELPHIA, PENNSYLVANIA.

AUTOMATIC TRAIN-STOPPING APPARATUS.

1,401,755.

Specification of Letters Patent. Patented Dec. 27, 1921.

Application filed June 30, 1919. Serial No. 307,509.

To all whom it may concern:

Be it known that I, ORAZIO BONACORSO, a citizen of the United States, residing at Philadelphia, in the county of Philadelphia and State of Pennsylvania, have invented new and useful Improvements in Automatic Train-Stopping Apparatus, of which the following is a specification.

This invention relates to improvements in automatic train stopping apparatus whereby when one car or train approaches another within a prescribed distance the car carried stopping mechanism on both cars or trains will be thrown into action automatically, incident to the proximity of the cars, whereby the propelling power of the cars will be cut off and the brakes applied.

In carrying out the present invention, it is my purpose to provide an apparatus of the class described whereby when one train approaches another from the front or the rear within a prescribed distance, the car carried stopping mechanism on both cars or trains as the case may be will be thrown into action to cut off the propelling power and effect an application of the brakes thereby bringing the cars or trains to a standstill and preventing a collision.

It is also my purpose to provide an automatic train stopping apparatus or system which may be installed and maintained at a comparatively low cost and which will operate effectively under all weather conditions.

With the above and other objects in view, the invention consists in the construction, combination and arrangement of parts hereinafter set forth in and falling within the scope of the claims.

In the accompanying drawings;

Figure 1— is a diagrammatic view of train stopping apparatus constructed in accordance with the present invention.

Fig. 2— is a rear side elevation of a locomotive cab showing the arrangement of the devices of the car carried stopping mechanism, parts of the cab being broken away to disclose this structure.

Fig. 3— is a vertical transverse sectional view taken substantially on the line 3—3 in Fig. 2.

Fig. 4— is a fragmentary enlarged side elevation of the locomotive throttle lever showing a detail of the invention.

Fig. 5— is a similar view of another portion of the throttle lever.

Fig. 6— is an enlarged fragmentary side elevation of the engineer's brake valve, and

Fig. 7— is a fragmentary plan view showing the arrangement of the conductors along the trackway on an enlarged scale.

In the present instance, I have shown the car carried stopping mechanism as applied to a steam driven locomotive and in this connection I wish it to be understood that the car carried stopping mechanism may be installed in electrically operated and other locomotives or motor cars.

Referring now to the accompanying drawings and in detail in Figs. 1 and 2, I designates the throttle valve lever of a steam locomotive, such lever being movable about the usual quadrant 2 and equipped with a locking dog engaging the teeth of the quadrant to hold the lever in the desired position. Disposed in proximity to the handle of the throttle lever 1 is the usual engineer's brake valve 3 by means of which the brake equipment of the car or train as the case may be is controlled. Suitably secured to the boiler shell of the locomotive within the cab is an electric motor 4 connected in an electric circuit 5 including a suitable source of electrical energy as, for instance, a dynamo 6. Fixed upon one end of the armature shaft of the motor 4 is a drum 7 to which is fastened and trained one end of a cable 8, such cable being carried over suitable guide sheaves 9 secured to the boiler shell and having the free end thereof passed through a bore 10 formed in the handle of the throttle valve lever 1 and connected with the manipulating handle 11 of the locking dog of the throttle lever. By means of this construction, it will be seen that when the circuit 5 of the motor is closed the latter will be energized to rotate the drum 7 thereby winding up the cable 8. In the initial movement of the cable the manipulating handle 11 of the locking dog is actuated to withdraw the locking dog from engagement with the teeth of the quadrant and in the continued winding of the cable the throttle lever is swung to close the valve thereby cutting off the motive power of the car.

The extremity of the armature shaft is equipped with a bevel pinion 12 meshing

with a similar pinion 13 loosely mounted upon the upper end of the stem of the engineer's brake valve 3 above the manipulating handle of such valve. Fixed to such stem 5 below the pinion 13 is a disk 14 having the upper surface adjacent to the periphery thereof formed with ratchet teeth 15 engaged by a pawl 16 secured to the under surface of the bevel pinion 13. In the rotation 10 of the armature shaft of the motor 4 to swing the throttle lever 1 to close the throttle valve as previously described, the bevel pinion 12 actuates the pinion 13 and the pawl 16 and ratchet teeth 15 on the disk 14 effect a rigid 15 connection between the bevel pinion 13 and the stem of the engineer's brake valve so that in the rotation of the armature shaft the brake valve is manipulated to effect an application of the brakes. By means of the pawl 20 and ratchet connection between the pinion 13 and the stem of the engineer's brake valve, the latter may be operated manually to cause an application of the brakes, while when the handle of the brake valve is moved 25 to release the brakes, the armature shaft of the motor rotates incident to the fixed connection between the stem of the brake valve and the bevel pinion 14, the latter acting to impart movement to pinion 13, through the 30 pawl, and therefore rotate pinion 12 on the armature shaft. This will produce slack in cable 8, the slack being taken up upon the next movement of the throttle lever to open position. Located upon one face of the quadrant 35 of the throttle lever is a spring switch comprising, in the present instance, a lever 17 pivoted at one end upon a stud 18 and equipped with an insulated handle 19 and adapted to engage a contact 20 secured to the quadrant, a coiled contractile spring 21 having one end secured to the lever 17 and the opposite end fastened to the adjacent face of the quadrant, such spring acting to maintain the lever of the switch in engagement 40 with the contact 20. Projecting outwardly from the throttle lever is a pin 22 adapted in the movement of the lever to closed position under the action of the motor to engage the handle 19 on the lever 17 and swing the lever 45 out of engagement with the contact 20. Terminal 18 of this spring switch is to be connected by wire 27 with the track brush or other conducting element 28, and terminal 20 is to be connected by a wire 4^a with brush 50 26 of motor 4. When the throttle lever is moved to close the valve, the spring switch will be opened by engagement between pin 22 and handle 19, throwing the switch blade out of engagement with contact 20 and breaking the motor circuit.

The electric circuit 5 for the motor 4 will be seen by reference to Fig. 1, to include a dynamo 6 mentioned heretofore and a brush 23 of the dynamo is connected with a conductor 24 to a brush 25 of the motor, the

other brush of the motor being indicated by the numeral 26, having connection with a conductor 27 which in turn is connected to a conductor wheel or element 28. 29, 30 indicate parallel lines of rails constituting the 70 track-way, also forming electric current carrying conductors. Between the rails 29, 30 are conductor sections 31, 32, having relatively insulated portions 33 with a portion 31^a of one section connecting with an opposite portion 31^b of the same section by a transverse connection 31^c, each conductor being in the nature of a step formation, to have one portion thereof for instance, extending a certain distance and then crossing 75 over and extending on another distance at the end of which it will be insulated from the next section, as clearly shown in Fig. 1. The truck wheels of the locomotive or vehicle operating over the rails 29, 30 are indicated 80 by the numerals 34, 35, and the truck axle or body forms an electric conductor and is indicated by the numeral 36. The dynamo 6 is operated by a shaft 37 which on its extremity carries a wheel 38 operating over the 85 track rail 30 thus generating the current which is to be subsequently applied to the motor 4 and by reference to Figure 1, it will be seen that the conductor element or wheel 28 spans the conductor sections 31, 90 32 at all times and operates over the same when the vehicle operates over the track-way. It will of course be understood that in Fig. 1, I have shown the electric connections for one vehicle on the left hand side and 95 similar electric connections for the vehicle on the right hand side and that when the two vehicles come within the prescribed distance namely within the extent of one of the conductor sections, a circuit will be closed to 100 bring about operation of the motor 4, although the dynamo of each unit will of course be operating all the time.

Now assuming that two trains have approached one another within a distance 110 shorter than the length of one conductor section, it will be seen that an electric circuit will be closed to operate the motor and this may be more clearly brought out by following the circuit from the brush 23^a of 115 the dynamo 6 commencing with the unit at the left hand side of Fig. 1. The path of the current therefore will be from the brush 23^a of the dynamo 6, through the conductor 36 and the truck wheel 35 to and along the 120 rail 30 to the truck wheel 35 of the other unit, axle 36, wire 27', brush 26, motor 4 of this right hand unit, brush or conducting element 25, wire 5, brush 23, generator 6, brush 23^a, wire 31' element 28 from which current 125 will pass through the portion 31^b of the section 31 and thence on through the cross connection 31^c to the portion 31^a of the conductor section 31, to the conductor element or wheel 28 of the left hand unit and then 130

up through the conductor 27, brush 26 and motor 4 and then through the brush 25 and conductor 24 to the other brush 23 of the dynamo. It will be seen that when the circuit 5 is closed in this manner the motor 4 will of course be placed in operation and will therefore actuate the cable 8 to exert a pull on the throttle 1 and at the same time through the medium of the pinions 12, 13, operate the 10 engineer's brake valve 3.

It will of course be understood that the 15 lengths of the conductor sections may be arranged as desired and varied to suit existing conditions and that although the dynamo 20 of every unit in the system will be in operation at all times that the vehicle is operating over the track-way, the motor 4 of each unit will not operate until the circuit is closed and then of course will be actuated to accomplish the desired result.

From the foregoing description taken in connection with the accompanying drawings, the construction and mode of operation of invention will be readily apparent. It 25 will be seen that I have provided an automatic train stopping apparatus or system whereby trains within the same block, that is to say, within the prescribed distance of one another, will be brought to a stop automatically.

While I have herein shown and described one preferred form of my invention by way of illustration, I wish it to be understood that I do not limit or confine myself to the 35 precise details of construction herein described and delineated, as modification and

variation may be made within the scope of the claims without departing from the spirit of the invention.

Having described my invention I claim— 40

1. In train stopping apparatus, the combination with a track-way divided into blocks, of car carried stopping mechanism comprising an electric motor, means operable from said motor for cutting off the propelling power of the car, a connection between said motor and the engineer's brake valve, means for operating the motors on cars within the same block whereby the propelling power will be cut off and the brakes 45 applied, and means operable to break the circuit of each motor simultaneously with the cutting off of the propelling power of the car, said means last named including a switch opened simultaneously with the closing of a controlling lever of the vehicle and operated by said lever.

2. In train stopping apparatus, car carried stopping mechanism comprising an electric motor, a connection between said motor and the engineer's brake valve, a drum fixed to the motor shaft, a flexible connection between said drum and the throttle lever of the engine whereby the latter will be closed by the operation of the motor, a circuit for the 60 motor, a spring switch in said circuit, and means carried by the lever for engaging the switch and opening the latter when the lever is thrown to closing position.

In testimony whereof I affix my signature. 70

ORAZIO BONACCORSO.
